UNITED STATES PATENT OFFICE.

EDMUND J. ANTHONY, OF BROOKVIEW, NEW YORK.

RAILWAY-RAIL-LOCKING MECHANISM.

941,692.

Specification of Letters Patent. Patented Nov. 30, 1909.

Application filed March 24, 1909. Serial No. 485,463.

To all whom it may concern:

Be it known that I, EDMUND J. ANTHONY, a citizen of the United States, residing at Brookview, Rensselaer county, New York, have invented certain new and useful Improvements in Railway-Rail-Locking Mechanisms; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

15 One of the objects of my invention is to provide a novel form of railway-rail chair adapted to be disposed in and be supported by a metal tie, also of peculiar configuration, and to be suitably removably locked thereto, 20 against accidental displacement or movement.

More particularly, the object is to provide a novel form of locking mechanism for the rails, whereby the latter are firmly locked 25 to the chair, which is, in turn, as above noted, securely locked to the metal tie; and whereby, should the metal ties sink somewhat into the road-bed, due to the heavy weight of the trains constantly passing there- 30 over, the adjustable rail-clamping members of my locking-mechanism may be moved to the proper position to maintain correct elevation of the railway-rail with respect to its next succeeding, or preceding, or adja- 35 cent, rail.

With these objects in view, and others appearing as the specification proceeds, my invention comprehends the novel construction, combination, and arrangement of parts, as 40 will be hereinafter fully detailed in the specification, summed up in the claims, and illustrated in the drawing.

In the accompanying drawing, forming part of my application for patent, and in 45 which like characters of reference denote corresponding parts throughout the several views: Figure 1 is a transverse vertical section through my improvements, certain parts being shown in elevation; Fig. 2 is an end view, in elevation, of my improvements; 50 Fig. 3 is a detached detail view of one of the adjustable rail-clamping members of my locking-mechanism; Fig. 4 is a section on the line 3-3, Fig. 3; Fig. 5 is a detached 55 detail view, in side elevation, of the railway-rail chair; Fig. 6 is a transverse sectional

view of the metal tie; and Fig. 7 is a detached detail view, in end elevation, of my chair.

Referring, now, in detail to the drawing: 60 although, as is obvious, the supporting means for the railway-rail D may be an ordinary wooden tie, I prefer to utilize, as such supporting means, a peculiar form of metallic chair and tie.

A indicates my metallic tie, which, as shown, preferably comprises the base a and two perforated side-flanges a', a' extending longitudinally of the tie; the tie being adapted to be disposed in the road-bed and 70 suitably ballasted, as is usual and well known.

Adapted to be disposed within the tie A is my improved form of chair B, comprising an upper, horizontal bridge or seat b 75 for the railway-rails, and depending side-flanges b', b', perforated, as shown at b², b², said flanges contacting with the flanges a', a' and being recessed toward their tops, as shown at b^{2x}, b^{2x} to form shoulders to receive 80 and bear upon the tops of flanges a', a'. Removably locking the flanges a', a' and b', b' together are rivets or bolts a², a². At each end of the flanges b', b' is a pair of depending strengthening-webs b³, b³ (one 85 pair thereof being shown in Fig. 2 and the other pair thereof in Fig. 7). Between each two webs of each pair is a channeled-out portion, or recess, or socket b⁴; and uniting the webs at one end with the corresponding 90 webs at the other end are a pair of integral strengthening braces b⁵ (Figs. 1, 2 and 7).

The adjustable rail-clamp members of my rail-locking mechanism comprise a pair of clamps C, C, having, each, a body-portion c^x 95 centrally apertured, as shown at c³, and a plurality of radially-projecting arms c, c', c² (in this instance, three arms are illustrated merely as an example) of varying lengths, measured from a line drawn from the central point of aperture c³ to the end; and bisecting the width of each arm, for a purpose presently appearing. Each said arm terminates in a flange or lug c⁴ bent at an angle to the plane of the arms c, c', c²; 105 one of said flanges, as required, being adapted to bear upon the top of the base d of the railway-rail D (in the drawing, the shortest arm, c, being so shown as bearing upon the railway-rail base,—the arm c' being the next 110 longer, and the arm c² being the longest).

Passing through the aperture c³ in each

clamp-member C and resting in the channel or socket b^4 and disposed between the braces b^5 is a bolt c^5 carrying a nut c^6 threaded on the bolt, and which may be tightened up to 5 form a rigid structure, as is obvious.

As will be seen in the drawing, the clamps C, C are disposed in a vertical position against the ends of the chair B.

Between the base d of the railway-rail 10 and the top b of the chair, a strip E of suitable material, such as wood, may be and desirably is disposed, subserving the dual function of a leveler for the railway-rail and a deadener of noise, to eliminate the 15 noise which would otherwise result from trains passing over the rails, if metal were placed upon metal.

The great advantage of my adjustable clamping-members C, C is apparent: If one 20 or more of the metallic ties A should sink somewhat into the roadbed, by reason of the weight of trains constantly passing thereover, all that is necessary to be done is simply to remove the strip of wood E, replace it by a piece of greater thickness, loosen the nut c^6 somewhat, revolve or turn the adjustable clamping-members C, C 25 around, so that another arm (such as c' , or c^2) is brought to bear upon the top of the rail-base d , and then tighten up the nut c^6 . It will be noted that, in this operation, there 30 is no necessity of going to the trouble and work of disturbing the position of the tie a , or the ballasting, and that the operation 35 is performed without interference with the metallic tie a , or the ballasting.

One of the features of my invention which distinguishes it in the art is the peculiar formation of my railway-clamp members C, 40 C, having the radially-projecting arms of differing lengths, for the purpose outlined.

The parts of my mechanism are few in number and are simple to manufacture, and can be sold at a reasonable cost; are strong 45 and durable in use; and are exceedingly efficient in operation.

Modifications in detail may be made, and, in fact, will readily suggest themselves to those skilled in the art to which this invention appertains; but all such changes and modifications as come within the terms of the appended claims constitute no departure 50 from the spirit of the invention, and are within the scope and purview thereof.

Having thus fully described my invention, what I claim as new and desire to secure by Letters-Patent is:

1. The combination with supporting means for a railway-rail, of railway-rail 60 clamping-members vertically disposed at opposite ends of said supporting-means, and comprising, each, a body portion having radially-projecting arms of differing lengths, any one of said arms being adapted to bear 65 against the base of the rail.

2. The combination with supporting means for a railway-rail, of railway-rail clamping-members vertically disposed at opposite ends of said supporting-means, and comprising, each, a body portion having radially-projecting arms of differing lengths, any one of said arms being adapted to bear 70 against the base of the rail, and means common to both said clamping-members for uniting said members against movement. 75

3. A railway-rail clamping-member comprising a body-portion having a plurality of radially-projecting arms of differing lengths, any one of said arms being adapted to bear 80 upon the base of a railway-rail, each arm being formed, at the upper end, with a flange bent at an angle to the plane of said arm.

4. A railway-rail clamping-member comprising an apertured body portion having a plurality of radially-projecting arms of differing lengths, any one of said arms being adapted to bear 85 against the base of a railway-rail, each arm being formed, at the upper end, with a flange bent at an angle to the plane of said arm, and means passing 90 through said aperture to lock said clamping-member against movement.

5. A pair of duplicate railway-rail clamping-members, each comprising a body-portion having a plurality of radially-projecting arms of differing lengths, any one of said arms being adapted to bear 95 against the base of a railway-rail; and means common to both said clamping-members for removably uniting said pair of clamping-members. 100

6. A pair of duplicate railway-rail clamping-members, each comprising an apertured body-portion having a plurality of radially-projecting arms of differing lengths, any one of said arms being adapted to bear 105 against the base of a railway-rail, and means common to both said clamping-members and passing through said apertures for removably uniting said clamping-members.

7. In a railway-rail locking mechanism, a 110 rail-chair having a channeled-out portion; duplicate rail-clamping members, each comprising an apertured body-portion and a plurality of arms radially-projecting therefrom and of differing lengths, any one of 115 said arms being adapted to bear against the base of a railway-rail; and a bolt common to both said clamping-members and passing through said apertures and disposed in said channeled-out portion and carrying an adjusting-nut.

8. In a railway-rail locking-mechanism, a rail-chair having a channeled-out portion; duplicate rail-clamping members, each comprising an apertured body-portion having a 125 plurality of radially-projecting arms of differing lengths, each arm being formed at the end with a flange bent at an angle to the plane of said arm and adapted to bear upon the top of the base of a railway-rail; and a 130

bolt passing through said apertures and disposed in said channeled-out portion and carrying an adjusting-nut.

9. In a railway-rail locking mechanism, a rail-chair having at each end a pair of depending strengthening-webs forming therebetween a channeled-out portion; duplicate rail-clamping members, each comprising a perforated body-portion having a plurality of radially-projecting arms of differing lengths; and a bolt passing through said apertures and disposed in said channeled-out portions and carrying an adjusting-nut.

10. In a railway-rail locking-mechanism, a rail-chair having, at each end, a pair of depending strengthening-webs forming therebetween a channeled-out portion; two strengthening-braces, each one uniting a web at one end with a corresponding web at the other end; duplicate rail-clamping-members, each comprising a perforated body-portion having a plurality of radially-projecting arms of differing lengths; and a bolt com-

mon to both said clamping-members and passing through said apertures and disposed in said channeled-out portions and carrying an adjusting-nut. 25

11. In a railway-rail locking mechanism, a metallic tie formed with a base and with two vertical, longitudinally-extending side flanges; a rail-chair having two depending, longitudinally-extending flanges disposed in contact with said side-flanges of the tie; means for locking the chair and the tie together; and a pair of duplicate rail-clamping members, each comprising a body-portion having radially-projecting arms of differing lengths; and means common to both said clamping-members for securing said rail-clamping members to the chair. 30 35 40

In testimony whereof I affix my signature in presence of two witnesses.

EDMUND J. ANTHONY.
